UNITED STATES PATENT OFFICE.

CHARLES C. WRENSHALL, OF ST. PAUL, MINNESOTA.

RAILWAY WATER-TANK.

SPECIFICATION forming part of Letters Patent No. 363,934, dated May 31, 1887.

Application filed January 22, 1887. Serial No. 225,086. (No model.)

To all whom it may concern:

Be it known that I, CHARLES C. WREN-
SHALL, a citizen of the United States, residing
at St. Paul, in the county of Ramsey and State
5 of Minnesota, have invented certain Improvements
in Railway Water-Tanks, of which the
following is a specification.

As railway water-tanks are usually constructed they are provided with a valve located
10 in the bottom thereof and communicating with the outlet-pipe, through which the water is
discharged as required into the tanks of locomotives on the track opposite the tank. The
objection to this construction are that access
15 to the valve can be had only when the tank is
empty, and that often the valve becomes defec-
tive, or a chip or other obstruction will become
lodged under the valve in such position that it
cannot be closed, and consequently the water
20 will run out of the tank, causing serious injury
to the tracks by washing out the track-bed or by
the formation of ice on the tracks. Another ob-
jection is that the mud and sediment from the
water that is pumped into the tank settles in
25 the bottom of the tank, forming an inclined
surface over the bottom, sloping toward the
valve-opening and causing muddy water pumped
into the tank to run directly to the valve. I
overcome these objections by pro-
30 viding tanks of this class with means by which
access may be had at any time to the valve
without removing the water from the tank for
the purpose of repairing it or removing ob-
structions therefrom, and by providing means
35 by which the valve is kept clear of the mud
and sediment that accumulates on the bottom
of the tank. I secure these objects by the
means hereinafter more particularly described,
and pointed out in the claims.

40 In the accompanying drawings, forming part
of this specification, Figure 1 is a sectional side
elevation of a railway water-tank embodying
my improvements. Fig. 2 is a detail section
of the box in the tank, showing the valves
45 closed.

In the drawings, 2 represents a railway wa-
ter-tank of any suitable or usual construction.
This tank is provided with an outlet-valve, 3,
which communicates with an outlet-pipe, 5,
50 that in turn connects with a swinging dis-
charge-pipe, 7. The valve 3 is provided with

suitable means for operating it, as the rod 9,
bell-crank lever 11, and cord or chain 13.

Within the tank and surrounding the valve-
opening I provide a suitable box, 15, that ex-
tends to the top of the water-space of the tank.
This box is made practically water-tight, and
may be of any suitable size, shape, or con-
struction. The tanks are usually provided
with a suitable roof, 17, with a floor, 19; below
55 the roof and at the top of the water-space.
The box 15 preferably extends to the floor 19.
A trap-door, 21, is provided in the floor at
the top of the box, through which access may
be had to the box.

60 In the wall of the box 15, at a suitable dis-
tance above the bottom of the tank, I provide
one or more openings, 23, through which the
water may pass from the main part of the tank
into box 15. I prefer to provide the box with
65 two openings, 23, in the opposite walls thereof,
at points substantially opposite each other.

The openings 23 are provided with suitable
doors or valves, 25, that are preferably hinged
70 to the walls of the box at the tops of the open-
ings and open outward into the main part of
the tank. These valves 25 are connected by
links 27 with an operating-rod, 29, that extends
upward through the box 15.

75 I prefer to connect the rod 29 with a suit-
able hook, 31, on the under side of the trap-
door, so that when the door is opened the
valves 25 will be closed, and when the door is
closed the valves will be opened. The pres-
80 sure of the water in the tank tends to close the
valves 25, and to hold them closed after they
have been shut by means of the operating-rod
already described. The valves 25 may be pro-
vided with a covering of leather, 33, or other
85 suitable material to serve as a packing when
the valves are closed.

90 The method of using this appliance will be
obvious. If the outlet-valve become ob-
structed by any substance, or if it become
defective and need repairs, the trap-door at
the top of the box can be opened and the doors
95 or valves 25 can be closed. When the oper-
ating-rod is connected with the door, the valves
will be closed as the door is opened. The wa-
ter in the box can be allowed to escape, and
100 the attendant can then descend into the box
and put the valve into working condition.

The inner wall of the box will usually be provided with a ladder to facilitate the descent into the box.

I have described the invention as particularly applicable to a railway water-tank, but do not wish to be understood as confining myself to its application to a tank of this class, as it may be applied to other tanks with beneficial results.

10 As the openings from the tank into the box 15 are at some distance above the bottom of the tank, the mud and sediment will settle in the tank below these openings, and the clear water will run into the box and pass out 15 through the valve-opening.

I claim as my invention—

1. The combination, with a tank of the class described, of an outlet-valve, a box surrounding said valve and extending above the water- 20 space of the tank, openings in the walls of said box, valves covering said openings, and means for operating said valves, substantially as described.

2. The combination, with a tank of the class described, of an outlet-valve, a box surrounding said valve and extending above the water- 25 space of the tank, openings in the opposite

walls of said box, hinged valves covering said openings, and an operating-rod connected with said valves and extending to the upper end of 30 said box, substantially as described.

3. The combination, in a tank of the class described, of an outlet-valve at the bottom of the tank, a box surrounding said valve and extending above the water-space, openings in 35 the walls of said box at a point above the bottom of the tank, valves covering said openings, and means for operating said valves, all substantially as described.

4. The combination, in a tank of the class 40 described, of an outlet-valve, a box surrounding said valve and extending above the water-space, openings in the walls of said box, valves covering said openings, a trap door at the upper end of said box, and an operating-rod connected with said valves and with said door, substantially as described, and for the purpose set forth.

In testimony whereof I have hereunto set my hand this 15th day of January, 1887.

CHARLES C. WRENSHALL.

In presence of—

E. W. OSBORNE,
A. C. PAUL.
